CHRISTMAS FLAG

Lewis Stuart, Philadelphia, Pa.

Application May 4, 1953, Serial No. 24,846

Term of patent 3½ years

(Cl. D29—17)

To all whom it may concern:

Be it known that I, Lewis Stuart, a citizen of the United States of America, residing at the city and county of Philadelphia, Commonwealth of Pennsylvania, have invented a new, original, and ornamental Design for a Christmas Flag, of which the following is a specification, reference being had to the accompanying drawing, forming part thereof.

The figure is a plan view of a Christmas flag showing my new design.

The reverse side of the flag is the same as that shown.

The flag is of conventional thickness.

Portions of the drawing are lined for color.

I claim:

The ornamental design for a Christmas flag, as shown and described.
